UNITED STATES PATENT OFFICE.

ROBERT G. BROWN, OF BROOKLYN, ASSIGNOR TO THE STANDARD MULTIPLEX TELEGRAPH COMPANY, OF NEW YORK, N. Y.

SYNCHRONOUS TELEGRAPHY.

SPECIFICATION forming part of Letters Patent No. 364,894, dated June 14, 1887.

Application filed January 26, 1887. Serial No. 225,520. (No model.)

To all whom it may concern:

Be it known that I, ROBERT G. BROWN, of Brooklyn, in the county of Kings and State of New York, have invented an Improvement in 5 Synchronous Telegraphy, of which the following is a specification.

In these improvements I make use of revolving arms, rotated with uniformity of speed and provided with trailers that are drawn over 10 circles of segments, so that the trailers are simultaneously upon corresponding segments in the two synchronously-moving instruments at the termini of the main line, and the segments are grouped together and connected to 15 exterior local and line circuits to operate the instruments included in such circuits. Trailers and circles of segments of this character with the segments grouped together are represented in Letters Patent Nos. 286,281 and 316,126.

20 My present improvements are especially intended for operating printing telegraph-instruments in connection with the synchronously-moving and circuit-closing trailers, whereby numerous local circuits containing 25 printing-instruments can be put into communication over one main line without interfering with each other, and so that the transmitting-instrument at one end of the line may act in connection with the proper printing-instrument 30 at the other end of the line, and the calls and signals made use of with printing telegraph-instruments and circuits can be employed, and there is the necessary pause or lapse of time after the setting of the type-wheel for the printing operation to take place, 35 and should the key of the transmitting-instrument be held down the same letter will be printed a second time when the trailer in traveling over the sunflower again reaches the segment connected with that key; or, if a number 40 of the transmitting-keys are held down simultaneously, the corresponding letters on the type-wheel will be printed in their regular order as the trailer comes in contact successively 45 with the segments in the sunflower connected to the keys that are held down, and it is nearly impossible to throw the instruments out of unison or to print a wrong letter, and this is true of all the printing-instruments and local 50 circuits that may be connected with the circles

of segments in the synchronous instruments at the respective ends of the line.

In the drawings I have represented in Figure 1 the circuit-connections at the two ends of a main line for one pair of printers. Figs. 55 2 and 3 illustrate modifications in the connections for accomplishing the same objects.

A and B represent the synchronous instruments connected together by the main line extending from one station to the other. Each 60 synchronous instrument is provided with a revolving shaft, C, an arm, D, extending therefrom, trailers 2 and 3 upon the arm, and two circular ranges of segments, 4 and 5. The inner circles of segments are intended to actuate 65 the type-wheels locally from the terminal or main offices independently of the main line, while the outer circle of segments are for the purpose of effecting the printing by currents coming over the main line. In each circle of 70 segments there may be any desired number—for instance, the circles having sixty segments may be adapted to ten local circuits with six segments to each circuit, the segments being connected up as indicated in the aforesaid 75 Patent No. 316,126.

I have shown six segments of the inner circle connected to the branch wires, three of which are connected to one branch and three to the other branch, and six of the segments of the 80 outer circle connected to a relay for effecting the printing and local circuits to the respective printing-instruments; but the number of segments connected together may be varied, and there may be any desired number of segments to compose the circle, but in all cases 85 the segments connected together into one circuit are preferably equidistant all around the circle.

At R R, I have shown a reversing-relay, at 90 T R a transmitting-relay, and at R a relay. M B represents the main battery, T B the transmitter-battery, L B a local battery, and R B a reversing-battery.

Referring to the connections shown in Fig. 95 1, the main line passes to the revolving shaft C and to the outer trailer, 2, for the segments 4. The local circuit, in which is included the local battery L B and the reversing-relay R R, which is preferably a differentially-wound po- 100

larized relay, starts from the inner trailer, 3, arm D, and wire to stop 10, armature 60, local battery L B, and through the reversing-relay R R in one direction, and wire 11 to three of the connected segments 5, and through the reversing-relay R R in the other direction, and wire 12 to the other three alternating segments, 5. The helices in this reversing-relay R R are wound in any desired manner, preferably differentially, so that when the current from L B passes through 60, 10, C D, and 3 to one of the segments 5 and the wire 12 to the relay R R the armature 14 will be swung in one direction, and when the current from L B passes through 15 60, 10, C D, 3 and one of the segments 5 and the wire 11 and through R R the armature 14 will be swung in the other direction, and this vibration of the armature 14 will be maintained by the action of the revolving trailer 3 and the 20 arms D revolving synchronously in the instruments A and B, the armatures 14 at the two ends of the line will swing in exact unison, and will be continuously vibrated so long as the circuit and branches from the battery L B is 25 not broken between 60 and 10. The six segments on the outside circle are all grouped together and are connected by wire 36, through relay R and wire 35 to armature t, which is normally against its top stop, m.

30 The printing-instruments are illustrated at F and H. These printing telegraph-instruments are to be of any desired character, but preferably the kind in which the type-wheels and unison are actuated by clock-work and 35 controlled by reversible currents. They may have two type-wheels with suitable mechanism for taking an impression from one or the other. This class of instrument is termed the "stock - quotation ticker," and is too well 40 known to require additional explanation here.

I have represented an escapement-wheel at 16, and the escapement and armature at 17. Said armature 17 is preferably polarized, and is pulsated between the poles of the type-wheel 45 magnets T M; and upon the shaft 18, that carries the escapement-wheel 16, and the ordinary type-wheel (not shown in the drawing) is an arm and trailer, 19, that travels over a circle of segments, 20, (known as the "sunflower,")

50 corresponding in number to the characters on the type-wheel, and from each of the sunflower-segments a wire connects with a key upon the ordinary key-board K, and the contact-bar of the key-board is grounded at G.

55 The press-magnet is indicated at P M, and the lever that carries the printing-pad and armature is indicated at P. Upon this lever P is a spring, 22, which in its normal position rests against the stop 23, and this stop 23 is 60 grounded through a key, 40, which is normally open, and the stop 23 also connected by a local line, 24, running from the place where the printing-instrument is located to the central station containing the synchronous 65 instrument A or B, and there it is connected to the helix of the transmitting-relay T R, and thence to the battery T B and ground.

From the armature 14 the local-line wire 25 passes to the switch 26, contact p², and through the type-wheel magnets T M, and through the 70 press-magnet P M of the printing-instrument, and to the ground.

There is a call-bell and its magnet at L, and the circuit for the same passes from the switch-contact 28 through the helix of L and a resistance, R h, to the ground.

Presuming that the parts are in the positions indicated in Fig. 1, and the armatures 14 are vibrating in unison at the two stations A B, currents pass from the reversing-batteries R 80 B by either of the stops 30 or 31, over the armature 14 and the local line 25, and through T M and P M to the ground, the reversing-batteries R B also being grounded at G. In consequence of these pulsating and reverse currents passing over the local lines 25, the type-wheels of the two printing-instruments F and H will revolve in unison, but the press-magnet P M will not be actuated because its magnet is so constructed and its armature so adjusted 90 as to be sluggish, as is usual in printing-instruments of this order. If, now, the operator at F depresses one of his keys, a circuit is closed from the ground through the key K, its wire and segment 20, and through the trailer 19, 95 when it arrives at that segment, and by the wire 33, spring 22, stop 23, wire 24, helices of transmitting-relay T R, and battery T B to the ground. This instantly causes the transmitter-armature t to be drawn on its lower stop, 34, 100 which is connected to one pole of the main battery M B, the other pole of which is grounded. The current from M B is thereby thrown on the main line through stop 34, armature t, relay R, wire 36, one of the segments 4, trailer 2, and arm D, and the relay R is thereby charged, attracting its armature 60 away from its back-stop 10. The circuit of the local battery L B and reversing-relay R R is thereby broken at 10, and the armature 14 remains against one of its stops 30 or 31. The type-wheel stands still and the prolongation of contact with either of the batteries R B sufficiently charges the press-magnet P M to actuate its armature P to take the desired impression from the type-wheel. At the distant instrument B the current from M B over the line passes through C, arm D, trailer 2, wire 36, relay R, wire 35, lever t, and its top-stop, m, to ground, causing the armature 60 to separate 115 from 10 and stop the pulsating of 14, so that the type-wheel at H is also arrested, and the prolongation of contact causes the press-magnet P M to take the impression of the corresponding character of the type-wheel at the 120 instrument H.

At station B the magnet T R is not brought into action because the keys at H are not actuated on, but at the instrument F the circuit from T B through 24 is broken at 23 by the downward 130 movement of the press-lever P. Hence the armature t instantly flies back, thereby disconnecting the main battery M B from the segments 4 and main line, and the armatures of

both relays R close contact with their back-stops 10, and the pulsation in the reversing-relays R R are re-established simultaneously, so that the press-magnets release their armatures and the type-wheels are again set in motion and so continue, and if a key, K, at F, is depressed, or several keys are depressed, the operations before described will take place successively as the trailer 19 closes contact

with the segments of the sunflower in succession. The receiving-operator (at the distant station H) can at any time break the sender by depressing his calling-key 40 or any of the transmitting-keys, thereby sending impulses from the main battery at B to the transmitting-station through the relays R, which break up the message being printed there.

I wish to remark here that, supposing the trailers 2 are passing over one of their segments 4 and at that instant the main battery M B is cut off at 34, the probability is that the relay R at the distant station would not receive a sufficient charge to actuate its armature, in which case the reversing-relay R R at that distant station would fail to make a pause and the letter or character would not be printed; but, in consequence of the contacts 22 23 being controlled by the printing-lever, the main battery is cut off automatically dur-

ing the time the trailer 2 is traveling between its segments and never when actually on a segment, thus effectually preventing the two printing telegraph-instruments losing their synchronous action from this cause and facilitating the rapid printing of the characters by not being compelled to release one key before depressing another key to print the next character. These printing-instruments are provided with unison-stops. (Not shown in the drawings.) They may be of any desired char-

acter. I prefer a unison in each that is brought into action by about three revolutions of the type-wheel and stops the further rotation until the unison-key is pressed and the movements of the printing-levers at the two instruments simultaneously remove the unison-stops and allow the type-wheels to start off together and the unisons are not brought into action unless the type-wheels are allowed to revolve several times without printing any characters. Unisons of this character are well known, and in my Patent No. 358,379 such a unison is illustrated at U, Fig. 1.

The trailer 2 is preferably adjusted on the arm D in advance, in a radial line, through the trailer 3, so that the trailer 2 reaches its segment before the trailer 3 reaches its segment, the object being to give the magnet R sufficient time to attract its armature 60 away from its back-post 10, so that when the trailer 3 reaches its corresponding segment the local circuit in which is included the reversing-relay R R is open at the armature 60 and post 10. Consequently the reversing-relay R R is not actuated, and its armature 14 remains against the stop 30 or 31, on which it was last thrown.

I put a condenser, C², in a shunt around the magnet R to prolong the magnetism of the same sufficiently to insure a positive break in the local circuit at 10.

When the printing-instruments are not in action, the switch 26 is to be turned to the contact 28, and the current will pass through the call or signal L; but the resistance R h is to be sufficient to prevent the batteries R B being consumed and the call will not be rung, as the pulsations of opposing polarity follow each other too rapidly to allow the bell-magnet time to be sufficiently energized; but when a party at one station desires to call up the distant station the key 40 is closed and opened thereby, the battery T B is placed in circuit through transmitter T R, whose armature t places the main battery M B on the line, the pulsations from which, through the relays R at both stations, cause their armatures 60 to make and break the local circuits at 10 and cause the pulsations from R B over 25 to be prolonged sufficiently to ring the alarms or calls L. Both persons place their switches 26 so as to close the circuits 25 through T M, the printing-instruments run to unison and stop, and the sender starts them simultaneously by depressing the ordinary unison-key in the transmitter K.

I have shown a rheostat, R h², in a shunt around T M P M, the resistance of which is to be sufficient to insure the proper action of the currents in T M P M. The object of the shunt is to prevent sparking between the armature 14 and its contacts 30 31, it being understood that sparks will not be developed by the discharge of the magnets T M P M when the circuit is broken at 30 or 31, because there is a metallic shunt around such magnets containing the resistance R h².

The devices shown in Fig. 2 correspond to those before described except in two particulars. The local circuit, in which is included the reversing-relay R R, is opened and closed by the trailer 2 and its segments only, in consequence of which the armature 14 vibrates back and forth uniformly whether letters are printed or not. The printing is effected by shunting out a resistance, R h³, normally in the local line, which causes an increase of energy sufficient to actuate the printing-magnet, as follows: When the circuit from T B through T R and 24 is closed by depressing one of the keys in the transmitting-instrument, the main-line circuit from the main battery M B is closed through 34 and t, and the wires 35 R and 36 and the armature 60 is drawn away from the back-stop 10, breaking the local circuit containing the local battery 62 and the helix of the magnet R⁴, so that the armature 64 flies back, closing a shunt at this stop 65 around the resistance R h³, which allows the current R B to pass without extra resistance through the wire 25 to the printing-instrument for sufficiently energizing the press-magnet to move the printing-lever P. These movements are necessarily instantaneous, so that the printing

is effected before the trailers 2 and 3 reach their next contact segments in the groups of segments, so that the entire movement of the press-lever takes place before the pulsating circuit from R B is reversed.

5 In Fig. 3 two distinct and independent features are illustrated. In the first the local battery L B is divided into two parts and placed in the branch circuits 11 and 12, so as to send alternating, positive, and negative currents through the reversing-relay R R, which in this case is wound in the ordinary way, throwing the armature 14 first one way and then the other. The second feature illustrates 15 the manner of connecting what is technically known as a "pole-changer," 74, which may be utilized with any of the plans here shown, and by means of which but one reversing-battery, R B, is required, the positive and negative 20 poles of which are alternately put to the local line and to earth, and are of equal strength. The magnet R^a and pole-changer 74 is actuated by the local battery 72 and armature and stop of the reversing-relay R R.

25 In all of the connections shown herein the currents on the local circuits from the synchronous instruments to the printing-instruments are pulsated, of reverse polarity, through the helices of the printers by the vibration of the 30 armature 14, and these local currents are independent of any main-line currents, so that there is little or no risk of error in the actuation of the type-wheels from failure in the current sent over the main line. The main-line 35 current has nothing to do in maintaining the unison of the distant printing-instruments, as they are kept in action by the respective synchronous instruments, and the main-line currents have only to cause those printing-instruments 40 to perform the printing, and the unison of the printers is not interfered with by momentary grounding, breaking, or interrupting the main line.

45 A condenser, 51, may be used, as shown in Fig. 3, in a shunt around the printer in place of the resistance R^b, Fig. 1.

I claim as my invention—

1. The combination, with synchronously-moving trailers and circles of segments and 50 the line-circuit, of printing telegraph-instruments, local line-wires, reversing-batteries, and circuit-changing armatures, a reversing-relay, and branch local circuits to the trailers for actuating the circuit-changing armatures, substantially as set forth..

55 2. The combination, with circles of segments and the circuit-connections for the same and synchronously-moving trailers and a line-circuit, of a reversing-relay, a local battery and branch circuits through the reversing-relays to the circles of segments, a reversing-battery and armature, a printing telegraph-instrument the magnets of which are in a circuit of the reversing-battery and armature, and a relay with its armature in the circuit of the local battery and its branches,

whereby the pulsations to the printing-instrument are arrested by the movement of the relay-armature breaking the local circuit to the synchronously-moving trailer, substantially as set forth.

3. The combination, with synchronously-moving trailers and their segments and branch circuit-connections to the segments, a reversing-magnet, and local battery, of an armature 75 to the reversing-magnet, a circuit passing through the same, a reversing-battery, a printing-instrument, and transmitter-keys and local line-circuit from the reversing-battery to the type-wheel and press-magnets, a main battery, 80 line-circuit, and a transmitting-relay and its battery and circuit passing through the keys of the transmitter, whereby the printing-lever is brought into action by the transmitting-relay, substantially as set forth. 85

4. The combination of two synchronously-moving arms and trailers, the circles of segments for the same, and the circuit-connections, two printing telegraph-instruments and their transmitter-keys, reversing-batteries, their local circuit-connections through the printing-instruments, reversing-relays and their armatures in the reversing-circuits, local batteries with their branch circuit-connections to one set of the circles of segments, relays with their 95 armatures to make and break the local branch circuits, and the main battery and line circuit passing through the relay and the other sets of segments and a local-line circuit and transmitting-battery to the keys of the printer, and a transmitting-relay for placing the main battery on line and effecting the printing, substantially as set forth.

5. In a printing telegraph-instrument adapted to use with synchronously-moving instruments and a line-circuit, the combination, with the type-wheel and impression-magnets, of a trailer and arm upon the type-wheel shaft, the sunflower-contacts, the range of transmitting-keys and the circuit-connections, 100 and a local line-circuit transmitting-relay and battery, and a circuit-breaker upon the printing mechanism to break the local line-circuit and demagnetize the transmitting-relay when the printing mechanism is moved, substantially 105 as set forth.

6. The combination, with a synchronously-moving arm and two trailers, of two circles of segments, the circuit-connections to segments forming groups, a local battery and the branch 110 circuit-connections to one circle of segments, and a reversing-relay in such local and branch circuits, a line, a main battery, circuit-connections from the same to the other circle of segments, and a relay with its armature in the circuit of the main battery, and telegraphic transmitting and receiving instruments in circuits connected with the relay and the reversing-relay, substantially as set forth. 115

7. The combination, with the synchronous 120 instruments and circles of segments, of a reversing-relay, local batteries and branch cir-

cuits for the same, a relay with its armature and stop in the local circuit, a battery and circuit passing through the relay, and a shunt to the relay and a condenser in the shunt, 5 whereby the condenser prolongs the break in the local branch circuits containing the reversing-relay, substantially as set forth.

Signed by me this 22d day of January, A. D.
1887.
